DESIGN FOR A GAME BOARD

Morris A. Bell, Oshkosh, Wis.

Application February 25, 1937, Serial No. 67,850

Term of patent 7 years

To all whom it may concern:

Be it known that I, Morris A. Bell, a citizen of the United States, residing at Oshkosh, in the county of Winnebago and State of Wisconsin, have invented a new, original, and ornamental Design for a Game Board, of which the following is a specification, reference being had to the accompanying drawing, forming part thereof.

The single figure is a plan view of a game board showing my new design.

As shown in the drawing, the design consists of an equal number of four differently colored squares. These squares are arranged with those of like colors forming continuous rows in one

diagonal direction with the rows following in regular sequence as to color; and with the rows in the other diagonal direction each consisting of squares from alternate rows running in said first designated diagonal direction so that each of said second designated rows consists of squares of two colors.

The article on which the design is used has no appreciable thickness.

I claim:

The ornamental design for a game board, as shown and described.

MORRIS A. BELL.
